UNITED STATES PATENT OFFICE.

CHARLES F. LEHMAN, OF MINNEAPOLIS, MINNESOTA.

TIME-CONTROLLED ELECTRIC DEVICE.

1,397,692.

Specification of Letters Patent.

Patented Nov. 22, 1921.

Application filed November 1, 1920. Serial No. 420,904.

To all whom it may concern:

Be it known that I, CHARLES FREDERICH LEHMAN, a citizen of Switzerland, residing at Minneapolis, in the county of Hennepin 5 and State of Minnesota, have invented certain new and useful Improvements in Time-Controlled Electric Devices; and I do hereby declare the following to be a full, clear, and exact description of the invention, such 10 as will enable others skilled in the art to which it appertains to make and use the same.

This invention relates to a time controlled electric device, and particularly to a device 15 whereby various electrical devices, such as lights, electric heaters, etc., may be actuated at various desired times and for various intervals.

It is an object of the invention to produce a device which will be controlled by an ordinary alarm clock which can be set to determine the time and interval through which it is desired to operate the electric device.

This and further objects and advantages 25 of the invention will appear as the description proceeds in connection with the accompanying drawings in which like reference characters refer to the same parts throughout the different views, and in which—

30 Figure 1 is a partial elevation and partial sectional view of the device as commercially constructed;

Fig. 2 is a somewhat diagrammatic plan view of the device and involved circuits;

35 Fig. 3 is a diagrammatic detail of some of the electric connections;

Figs. 4 and 5 are diagrammatic views illustrating the electrical contacts of certain parts; and

40 Fig. 6 is a view in vertical elevation showing other contacts used in the device.

Referring to the drawings, and particularly Fig. 1, the device of the invention is seen to comprise a box or casing *a* and an 45 alarm or other suitable clock *b*, a transformer *c* located in the box *a*, an electro-magnet *d* and a ratchet spool *e* operated by the electro-magnet *d*, both of which mechanisms are also located in the box *a*. An 50 electrical socket *f* is shown to which may be attached any suitable, or desirable electric device which it is desired to operate, such as a lamp *g* shown.

In Fig. 2 is illustrated an ordinary clock-work mechanism designated as 1, which has 55 the wheels 2 and 3 suitably driven thereby

and which represent the alarm wheels usually supplied with an alarm clock. The common type of alarm clock has but one alarm setting device and one alarm wheel, 60 and while applicant's device may be operated by one such wheel, it is preferably constructed with an additional or a total of two alarm wheels. The wheels 2 and 3 make one revolution in twelve hours and are equipped 65 with contact members 4 and 5, respectively. Each of the wheels 2 and 3 is equipped with a cylindrical cam member 5^a and co-operating cam follower or dog 6. As the wheels revolve, the member 6 rides on the edge of 70 the cam 5^a until the time arrives at which the device is set to be operated, when it drops into a notch formed in said cam. This is a common and well known construction in alarm clocks. As shown in Fig. 6, a 75 spring 7 presses on the wheel 3 and when the dog 6 drops into its notch, this spring projects the wheel slightly outward on its axle and the upper end of the spring contacts the arm 5. The wheel 2 is also urged outwardly 80 by a spring, and when its dog drops into the slot in the cam, said wheel is pushed out directly against the arm 4 and makes electrical contact therewith. The contacts of the wheels will continue until the dogs again 85 ride out of the cam slots.

The making of the above described contacts is arranged to operate the electrical portions of the device. The said contacts are electrically connected by suitably placed 90 wires with certain of the contact members on spool *e*. The spool *e* forms a rotating switch and has a central shaft 8 rigidly secured thereto which is mounted for rotation in suitably spaced brackets in the box *a*. 95 The spool is provided with a pawl and ratchet mechanism designated as 9 which is operated to intermittently revolve the spool by the oscillation of the lever 10. This lever 10 is suitably connected to the armature 11 of the electro-magnet *d* so that it will be oscillated each time the said magnet is operated and will turn the spool *e* one step. The spool *e* has an enlarged notched wheel 12 at one end, and the notches are arranged 105 on the periphery thereof and formed as ratchet teeth and successively engage the contact member 13 as the spool revolves. As shown in Figs. 2 and 4, each alternate tooth of the wheel 12 is equipped with an 110 electrical conductor which is in electrical communication with a conducting sleeve 14.

on the spool with which the contact finger 15 constantly engages. The contact fingers 13 and 15 are connected in the circuit which operates the lamps *g*, or other electrical device, the operation of which it is desired to control. This circuit is shown in Fig. 2 as including a battery 16 which may be used in various desired places, but where commercial current is available, the same will 10 ordinarily be used to control the lights or other electrical devices in a building where the invention is used.

At the other end of spool *e* is a similar ratchet shaped wheel 17 the teeth of which 15 are equipped with electrical conductors, as shown in Fig. 5 and each alternate one of said conductors will be connected to a contact ring 18 on the spool, while the conductors on the intermediate teeth will be 20 connected to the ring 19. Contact fingers 20 and 21 are disposed to respectively engage the rings 18 and 19, and another contact finger 22 successively engages the conducting members on the teeth of wheel 17. 25 The contact fingers 20 and 21 are electrically connected, as shown in Fig. 2, to the contact arms 4 and 5, respectively, which connection, as stated, will be made by suitably disposed conductors.

30 In order that the heavy voltage which will be sometimes used to operate the lights and other electrical apparatus will not have to be connected to the clock mechanism, a transformer *c* is provided and a primary coil 23 35 of the same is connected in circuit with a suitable battery 24. One side of this battery will be connected to the framework of the clock and will thus communicate with wheels 2 and 3. The other side of the battery is 40 connected to one terminal of the primary coil 23, the other end of which is, in turn, connected to contact finger 22. The ends of the coils of the electromagnet *d* are connected to the ends of the secondary coil of 45 the transformer *c*.

In the commercial embodiment of the device, the conductors connected to arms 4 and 5 are arranged to pass through or around the legs 25 of the clock and thence 50 into the box *a*. The battery conductor can also be arranged to pass through or around the leg 26. The battery 24 may or may not be installed in the box *a*.

The operation of the device is as follows: 55 Assuming the lights *g* are not lighted, the finger 13 will be in engagement with one of the non-conducting teeth on wheel 12 and the arms 4 and 5 will be out of contact with wheels 2 and 3. The clock is now set so that 60 one alarm wheel will operate at the time at which it is desired to light the lamp and the other alarm wheel will be set for the time at which it is desired to extinguish the lamps. When the first wheel arrives at the 65 set time, contact will be made with arm 5.

This will close the contact through the battery circuit, including the primary part of the transformer, contact fingers 20 and 22 and ring 18. The current will be induced in the secondary of the transformer and the 70 electromagnet will be given one actuation. This will move the wheels 12 and 17 one notch. The contact finger 13 will be moved to a conducting tooth on wheel 12 and the circuit will be closed through the lamps and 75 light the same. The lamps will now remain lighted until the wheel 2 reaches the set point when contact will be made with the finger 4. It will be noted that when the wheel 17 was moved one notch, the battery 80 lead connected to finger 22, was transferred from ring 19 to ring 18, since alternate teeth of wheel 17 are respectively connected to rings 18 and 19. The battery circuit was thus opened and will be closed again when 85 contact is made with finger 4. This will result in another actuation of the electromagnet through the transformer and the spool *e* will be moved another notch. Contact finger 13 will now move to a nonconducting 90 tooth, the circuit through the lights will be broken and the same will be extinguished. The wheel 17 will again switch the battery current to ring 19 and the battery circuit 95 will be opened.

The transformer is used so that an effective and powerful action by the electromagnet will be obtained without the use of a correspondingly heavy battery circuit. The positive operation of the ratchet device will 100 be assured by the strong electromagnet. If desired, suitable non-sparking metal may be used for the various contacts, or a condenser may be interposed in the circuits to quench any sparking tendency. 105

From the above description it would seem that applicant's device has a wide range of utility and provides a simple and inexpensive means whereby various lighting systems, either in dwellings, store windows, or electric signs, may be lighted at any desired time and for any desired period. The device may also be set to operate an electric heater at an early hour in the morning so that a room may be heated before the occupants thereof arise. Various other forms of electrical apparatus can also be conveniently operated by means of applicant's invention. 110

115 It will be understood that various changes in the arrangement and details of the device may be made without departing from the scope of applicant's invention, which, generally stated, consists in the matter shown and described and set forth in the appended claims.

120 What is claimed is:

1. A device of the class described having in combination a pair of time-controlled contacts, a second pair of time-controlled contacts, a switch member, an electro-magnetic 125 130

- means for operating said switch member, an electrical circuit connected to said pairs of contacts and said switch and connected to said electro-magnetic means through a transformer, a second electrical circuit for controlling an electrical apparatus, said circuit also connected to said switch member, said switch member being constructed and arranged to be actuated to close the last mentioned electrical circuit when the first pair of time-controlled contacts are closed and to be so set by such actuation that it will be again actuated to open the last mentioned circuit when the second pair of time-controlled contacts are closed.
2. A device of the class described comprising clock-work mechanism, a plurality of sets of contacts operated thereby, an intermittently operated switch member, an electro-magnet, mechanism for intermittently moving said switch member propelled by said electro-magnet, an electrical circuit including the sets of contacts, the electro-magnet and the switch member, a second circuit adapted to be closed and opened by said switch member, said switch member being constructed and arranged so that when one set of contacts is closed the second circuit will be closed through the switch member and the switch member so set that when another pair of contacts is closed the second circuit will be opened through said switch member.
3. A device of the class described having in combination a pair of time-controlled contacts, a second pair of timed-controlled contacts, a switch member comprising a disk having thereon a series of contacts and insulated portions, step by step operating means for said switch member adapted to operate said switch one step each time either of said pairs of contacts are closed, an electric circuit connected to said contacts, said operating means and said switch member, a second electrical circuit connected to said switch member and arranged to be opened and closed by alternate operations of said switch, said circuit being adapted to control an electrical apparatus included therein, said switch member being constructed and arranged to be actuated one step to bring a contact into operative position when the first pair of contacts are closed to close said second circuit and to be so set that it will be again actuated one step when the second pair of contacts are closed to bring an insulated portion into position to open said second circuit.
4. A device of the class described having in combination, two sets of time controlled contacts, an intermittently operated switch, mechanism for operating said switch, an electrical circuit including said contacts, a transformer and an electromagnet operated thereby, said operating mechanism being actuated by the electromagnet, said circuit and switch member constructed and arranged so that when one set of contacts is closed the switch will be actuated and moved to a position so that it will be again actuated when the other set of contacts is closed.
5. A device of the class described comprising two sets of time controlled contacts, a movable switch comprising a cylindrical member and a ratchet toothed wheel at one end thereof, a pair of contact rings on said cylinder, the teeth of the ratchet wheel carrying conductors and alternate teeth being connected respectively to each of said contact rings, an electrical circuit having connection with said sets of contacts, the ratchet wheel, the contact rings, and mechanism for operating said switch constructed and arranged so that when one set of contacts is closed the circuit will be closed through the ratchet wheel and one ring to actuate the switch and open the circuit and also set the switch so that when the second pair of contacts is closed the circuit will be closed through the ratchet wheel and the other ring and the switch will be again actuated, the circuit opened and the switch set so that it may be again operated as before.
6. A device of the class described having in combination an intermittently rotating switch comprising a cylindrical member having at each end thereof similar ratchet toothed wheels, a pair of spaced contact rings on said cylinder, all of the teeth of one ratchet wheel having conductors thereon which are alternately connected, respectively, with each of said contact rings, a third contact ring on said cylinder, each alternate tooth of the other ratchet wheel carrying a conductor which is connected to the third ring, the other teeth of said wheel being insulated, an electrical circuit including contact fingers to successively engage the teeth of the last mentioned ratchet wheel and also a contact to engage the third contact ring, another electrical circuit including a contact finger adapted to successively engage the teeth of the first mentioned ratchet wheel and having contact fingers engaging the first mentioned rings, mechanism for intermittently rotating said switch so that the first mentioned circuit is successively closed and opened and the last mentioned circuit is successively closed through the teeth of the ratchet wheel and one of the pair of contact rings and then through the teeth of the ratchet wheel and the other of the pair of contact rings.
7. A device of the class described having in combination two sets of time controlled contacts, an intermittently operated switch member connected to one of each set of contacts, mechanism for operating said switch member, an electromagnet for actuating said mechanism, a transformer to the

secondary of which the electromagnet is connected, the primary of the transformer being connected to the switch member, and the other of each set of contacts, an electrical circuit arranged to be successively closed and opened by said switch member, said switch member being constructed and arranged so that when one set of contacts is closed the circuit will be closed and the 10 electromagnet will be operated through the transformer to move the switch to open said electrical circuit and set the switch so that when the second set of contacts is closed the circuit will again be closed and switch actuated by the electromagnet to open said circuit and be set in a position similar to its 15 original position.

8. A device of the class described com-

prising a cylindrical switch having spaced toothed wheels thereon, one having contacts 20 on each tooth and the other having contacts on alternate teeth, contact members engaging said wheels, a pair of contact rings on said switch connected, respectively, to alternate contacts on the first mentioned wheel, 25 and a contact ring connected to the contacts on the other wheel.

9. The structure set forth in claim 8, contact fingers for engagement with said contact rings, and means for intermittently 30 actuating said switch to variously control circuits connected to said contact members and fingers.

In testimony whereof I affix my signature.

CHARLES F. LEHMAN.
